UNITED STATES PATENT OFFICE.

CHARLES H. HAGOPIAN, OF SPRINGFIELD, MASSACHUSETTS.

ADJUSTABLE SEAT.

Application filed December 7, 1923. Serial No. 679,230.

To all whom it may concern:

Be it known that I, CHARLES H. HAGOPIAN, a citizen of the Republic of Armenia, residing at Springfield, in the county of 5 Hampden and State of Massachusetts, have invented new and useful Improvements in Adjustable Seats, of which the following is a specification.

The invention relates to adjustable seats 10 and particularly to the type having a support and a seat movable therein that is adapted to be held in various positions of adjustment.

The object of the invention is the provision of a device that is easily moved by hand to any desired adjusted position and in which it is held by means associated with the support and seat.

Another object of the invention is the provision of holding means that are released from holding engagement as the seat is moved to its most elevated position and that allows the seat to be lowered without the manual disengagement of the holding mechanism. Other objects and advantages will be obvious from the following description and accompanying drawings in which:

Fig. 1 is a side elevational view of an adjustable seat embodying my invention,

Fig. 2 is a sectional elevational view taken on line 2—2 of Fig. 1,

Fig. 3 is an enlarged sectional view taken on line 3—3 of Fig. 2, and

Fig. 4 is an enlarged elevational view of 35 a portion of one of the guide members showing the pawl pivoted thereto, and Fig. 5 is a perspective view of the holding plate.

Referring to the drawings in detail the invention will now be described.

40 Upright posts 1 are provided that are disposed two at either end of support. They are secured rigidly together by the side bars 2 and end bars 3 in such a manner that they form a rigid seat supporting member. The said posts are shown as being rectangular

in cross section but may be made in any form desired or ornamented in any desired manner. Other end cross bars 4 are secured to the posts 1 at the ends of the support and are spaced from the members 3 as best shown in Fig. 3. The space between the inner or adjacent faces of the said members 3 and 4 serve as guideways 4' for the tongues 5 of the movable seat 6.

55 The said seat 6 preferably comprises a flat bench-like member as shown having two

downwardly extending guides or tongues 5 that are slidably carried in the before mentioned guideways 4'. The seat by the means of the said tongues and guideways is held 60 in a level plane during a lowering or raising movement. Holding plates 7 are fixed to each of the posts 1 at a point adjacent the ends of the guideways 4'. These plates 65 comprise a substantially flat rear wall that is encircled by side and end walls or flanges 9 and 14. A central bar portion B is carried by the plate 7 that is provided on its forward face with holding notches 8 while the ends of the bar portion is curved 70 at 16 and 17 as best shown in Fig. 5. The side wall 9 of the plate is preferably shaped to form nose guides 10 adjacent the holding notches 8 while the wall at the rear of the bar is spaced from the rear side 7' 75 of the bar portion B to form a guideway 15 therewith.

Pawls 11 pivoted at each end of the tongues 5 by the means of screws 12 or the like carry on their outer end a notch engaging pin or plug 13. As the seat is grasped by hand and raised to an elevated position, the nose portions 10 of the plates guide the pins 13 into the various notches 8 and in any one of which the pins may rest to 85 support the seat in an elevated position.

In operation the seat 6 is grasped by the hands for a raising movement and the pawl pin is guided by the nose portion 17 into the various notches 8 whereby the seat may 90 be supported by the pawl and notches in various elevated positions. To lower the seat it is raised to the limit of its movement wherein the pawl pin 13 strikes the curved portion of the flange at 19 and which prevents a further raising movement. The seat may then be lowered to its lowermost position during which movement the pawl and pin are guided into the channel 15 by the means of the guiding curved end 16 of the 95 plate.

It will be readily obvious that many changes may be made in the form of the invention without departing from the scope thereof and I therefore prefer to be limited 105 by the appended claim rather than by the foregoing description.

What I claim is:

An adjustable seat comprising, in combination, a support having vertical guideways 110 at the ends thereof, a seat having rigid guides depending therefrom that are slid-

able in said guideways, whereby the seat may be moved vertically of the support, pawls pivoted at opposite sides of each of said guides, plates carried by the support at either end of said guideways each having a central boss portion that is provided with pawl engaging notches in one side thereof and a flange extending around the boss to form a notch guide at the notched side of

the boss and a channel at the rear side 10 thereof, whereby the pawls are guided into the notches during a raising movement of the seat and into the channel and away from the notches during a lowering of the seat.

In testimony whereof I have affixed my 15 signature.

CHARLES H. HAGOPIAN.
